UNITED STATES PATENT OFFICE.

BRUNO SALZER AND GUSTAV WALTHER, OF CHEMNITZ, GERMANY.

STRAIGHT-BAR KNITTING-MACHINE.

No. 916,492.

Specification of Letters Patent.

Patented March 30, 1909.

Application filed November 11, 1904. Serial No. 232,317.

To all whom it may concern:

Be it known that we, BRUNO SALZER and GUSTAV WALTHER, subjects of the German Emperor, residing at Chemnitz, in the Kingdom of Saxony and Empire of Germany, respectively, have invented certain new and useful Improvements in Straight-Bar Knitting-Machines, of which the following is a specification.

- 10 This invention relates to straight bar knitting machines of the Cotton type, and more particularly to an auxiliary patterning mechanism for producing longitudinal stripes. The construction and operation of 15 the frame needles and thread-guides are well known; but the mechanism is new which moves the thread-guides of the plating-threads to and fro for the purpose of causing the thread-guides at each operation to 20 reach the place where the plate-thread is to be put around the frame needles in order to produce a point of the pattern.

In the annexed drawings the invention is represented.

- 25 Figure 1 is a front view of the right side of a straight bar knitting machine showing the last two divisions X' , X'' with the plating device and the auxiliary patterning mechanism Y for producing the longitudinal stripes. The latter forms the principal feature of the invention, and the greater part of Fig. 1, with the divisions X' , X'' which are well known, only serves for the purpose of explaining the mechanical relation between the new apparatus and the old machine. Fig. 2 shows a side-view of the new patterning mechanism indicated as Y in Fig. 1 being a side-view from the right. Fig. 3 is a cross-section on line 3, 3, of Fig. 40 1 through the old well known part of the Cotton machine seen from the right for the purpose of illustrating in what manner the thread-guides may co-operate with the frame needles when they are moved to and fro by the 45 main patterning mechanism shown in Fig. 2. Fig. 4 is a repetition of some of the most important parts of Fig. 2, consequently also a side-view seen from the right. Fig. 5 is a front view of the same parts and consequently a repetition from Fig. 1, on a somewhat larger scale, for the purpose of clearer illustration. Figs. 6, 7 and 8 respectively are side-view, front-view and top-view of Figs. 4 and 5. Fig. 9 is a diagram of a pattern produced by means of the present device. Fig. 10 is a sectional view with parts omit-

ted and showing means for operating the wedge bar and arresting member. Fig. 11 is a view looking in the direction of the arrow 11 of Fig. 12. Fig. 12 is a view looking in the direction of arrow 12 of Fig. 11. Fig. 13 is a detail view of one of the parts shown in Figs. 11 and 12.

To a rod A, Figs. 1 and 3, traversing all the length of the machine, at each division X' , X'' a double-lever B is fixed. Each of these pairs of levers B carries a thread-guide bar C. To these thread-guide bars C the thread-guides D are attached in a well known manner. From the plate-thread spools C¹, C² arranged above C the plate-threads are conducted through the thread-holes D³ of the thread-guide D. In Fig. 3 the thread-guides D are represented in their position of rest.

The rod A to which the parts B, C, D are fixed may be lifted from the machine and kept at an elevated position when not in use. For this purpose the forked pieces G, H are arranged which serve as supports for the rod A and the pins J for enabling a rapid removal and replacement of said parts. The forked piece G is arranged at the upper end of a slide L movable in the two supports G¹ and G² and adapted to be moved up and down. Both supports are fixed to the lever G³ integral with the hub G⁴ and attached to the shaft E. Consequently if the shaft E is rotated by mechanism to be explained later on the thread-guides D must partake in this movement also. Fixed to the slide L adapted to be moved up and down is the pin J while the lower forked end H of the lever A¹ keyed to the rod A fits on said pin J.

The thread-guides D when arranged in the machine as shown in Figs. 1 and 3 receive their operative movements from the main shaft K of the machine whereby the main patterning mechanism A B C D oscillates around the shaft E. For on the shaft E to which the levers G³ are fixed also the lever M is fixed which is provided with a rotatable roller M¹ and a draw-spring M² so that the roller M¹ is continuously pressed against the circumference of the cam M³ by said spring M². Consequently the shaft E and the patterning mechanism A B C D oscillate according to the form of the cam-perimeter M³. Pivoted to the machine-frame is another shaft F to which the levers F¹ and F² are fixed. The lever F² is provided with a roller F³ and a draw-spring F⁴.

constantly pressing the roller F^3 against the perimeter of the cam F^5 . The end of the lever F^1 presses under the lower end of the slide L at the upper end of which the rod 5 A rests with the patterning mechanism. Consequently when the levers F^2 and F^1 oscillate the slides L also must move up and down and in this manner the main patterning mechanism is operated by the two cams 10 M^3 and F^5 . M^3 oscillates the mechanism to and fro, and the cam F^5 imparts the up and down movement. Besides these two movements the thread guides D have a third movement, to wit in the longitudinal direction 15 of the rod A . For this purpose the rod A is moved to and fro in the forked pieces G and thereby the lever A^1 attached to the rod A is also moved to and fro on the pin J . This movement of the rod A is effected by 20 the auxiliary patterning mechanism consisting of the present invention to be explained in detail in connection with Figs. 4-8.

The operation of reproducing the pattern takes place in the well known manner, to 25 wit, the thread-guides D , oscillate about the shaft E and enter between the frame-needles N , then place the thread for two frame needles N to the left or right by means of a lateral movement of the rod A and then return 30 to a point in front of the frame needles, as indicated in Fig. 3. In this position of rest, Fig. 3, the thread-guides D remain till the sinking of the loops and the formation of a new row of loops has taken place. They 35 are then laterally moved to another point of the pattern and the same operation is repeated. The loop thus placed around a certain number of needles is knocked over on the formation of the following row of loops 40 and appears as a plated loop on the surface of the fabric. It will be noted that this formation of plated loops *per se* does not form a part of the present invention, but is well known. However the auxiliary patterning 45 mechanism, Figs. 4-8, which removes the thread-guides to the right and left for the purpose of producing the plated loops at certain parts of the pattern is new. Therefore the rod A , which carries the main patterning mechanism must be reciprocated longitudinally for a double purpose. First so 50 that the thread guides D engage between the frame needles N in the manner above described, then place the thread around one or 55 two frame needles N and effect a return to their position of rest, Fig. 3, which may be called a stitch forming movement. This movement of the thread guides D and this purpose also are well known. But besides 60 this the thread guides D must be moved for another purpose, to wit, to change the working position of the thread guides.

In Fig. 9 the small angle-hooks indicate the loops which are applied to the fabric by 65 the thread guides D . A number of these

loops are intersected by line $x-y$. All pattern loops in the line $x-y$ are produced by the main pattern mechanism in the well known machines which are not provided with the device of my invention. For it is to be kept in mind that for the purpose of producing these loops situated in a single straight line the thread guides D need only effect one of the movements above described for the first of the two purposes. But the second movement for the second one of the two purposes is to produce the pattern according to requirements in a zigzag line to the right or left of the central line $x-y$, as shown in Fig. 9. 70

The rod A carries on its inner end two fingers 15 and 16 which embrace and have loose working connection with a drive plate 17. Said plate is secured to one end of a shaft n which is mounted in bearings in the machine frame and adapted to be longitudinally reciprocated therein. The fingers 15 and 16 are of sufficient length to permit the rod A to oscillate to and fro and reciprocate up and down and at all times maintain connection with the plate 17. A yoke m secured to the shaft n is provided with bearings m' in which a short shaft g is mounted. Upon shaft g a pattern cam P is loosely secured and is provided with an oscillation pin t and oppositely projecting extensions P' provided with cam surfaces formed in the following manner. Each end is provided with eight parallel companion steps P^2 of uniform diametrical length, steps diverging from the axis of the cam in transverse planes *i. e.* each of said steps diverge from the axis in a vertical plane from points $a' b'$ to $c' d'$ respectively. Each of said steps P^2 is provided with five transverse steps p^3 . From the foregoing it will be seen that cam engaging members co-operating with any of the stepped or transverse faces of the cam P , on a horizontal line intersecting the axis of said cam, will engage surfaces always an equal distance apart thereby providing means whereby cam engaging members spaced apart a constant and equal distance may engage any of the companion stepped or transversely stepped faces without necessitating the changing of adjustment of said members. For instance, if the cam members engage the two companion steps a and b they can be engaged with any of the steps intervening the same and the steps b' and c' without separate adjustment. If the cam member P is oscillated on its axis the increased radial length of the transverse steps near b compensate for the decreased radial length of steps near d . We will now 95 explain the devices adapted to co-operate with said cam which, in the form shown, comprise two pincer like arms i pivotally mounted on shaft h and normally held apart by springs i' . Said shaft h is desirably fixed 100

in bearings h' , one thereof being shown in Fig. 4. Each of said arms carry at their upper end cam engaging rollers e f adapted for coöperation with these stepped faces p^2 p^3 . Said arms are also provided with oppositely projecting lugs carrying retaining rollers k adapted for engagement with opposite faces of a reciprocating wedge l . Said wedge is provided with converging surfaces l' at its upper end. When the rollers k engage the opposite parallel surfaces of the wedge l as shown in Fig. 5 the rollers e and f are held a sufficient distance apart to engage any of the companion stepped spaces p^2 or p^3 . It will be seen that when the wedge l is reciprocated downwardly so that the rollers k engage the surfaces l' the springs i' will pull the levers i outwardly in opposite directions out of contact with the cam P thereby permitting adjustment of the cam P longitudinally.

Next describing the means whereby the cam P is reciprocated longitudinally of its axis and oscillated thereon the same consists of the following operative mechanism. Upon the forward lower face of the cam P there is provided a hook p adapted to engage a lug q formed upon a lever s which is pivotally mounted at r and held in a normally retracted position by a spring r' secured to said lever and to any suitable stationary part. Said lever also carries a roller s' adapted for engagement with a projection s^2 upon the wedge block l . Now it will be seen by reference to Figs. 4, 5 and 10 that the wedge block l will, through the medium of the cam surfaces l' , release the levers i and permit the same to swing outwardly from the cam P before the cam surface s^2 engages the roller s' therefore when the latter, with the lever s , is forced outwardly reciprocating the cam P in a like direction the rollers will have been previously disengaged from said cam. It will be further seen that upon upward reciprocation of wedge l the rollers k will be engaged bringing the rollers e and f toward each other and into engagement with the cam P . Supposing that the cam P is moved in the direction of the arrow x^2 (Figs. 4 and 8) the rollers e and f bearing on the fourth companion steps p^2 as shown in Figs. 4 and 8 so that the rollers are brought into engagement with the outer cam surfaces near b' c' , this will result in bodily moving the cam in the direction of the arrow x^4 Fig. 8 and a like movement of shaft n to the right. If the cam P is moved in the direction of the arrow x' (Fig. 4) bringing the rollers in engagement of the cam surfaces a' d' (Fig. 8) there will be a bodily movement of the cam and shaft n in the direction of the arrow y' shown in Fig. 5.

We will next describe the manner in which horizontal movement of the rod A is effected by oscillating the cam P .

A lever u is provided having a loop portion u' which straddles shaft n , said lever at its lower end (Fig. 2) being connected at v with a lever v' provided with a cam roller r^2 engaging a cam r^3 and which is held in engagement therewith by spring r^4 . The lever u is provided with a slotted projection u^2 (Fig. 5) in which the oscillating pin t projects. Now it will be obvious from the foregoing that as the cam r^3 reciprocates the bar u the latter will impart an oscillating movement to the cam P which serves, after the rollers e and f have been adjusted and engaged with one of the pairs of companion steps P^2 to bring the transversed stepped faces p^2 into engagement with said rollers thereby imparting a longitudinal movement to shaft n in proportion to the depth of and number of transverse steps engaging said rollers. The part l is reciprocated through the medium of an arm l^2 (Fig. 1) provided with a cam engaging member l^3 engaging a cam l^4 .

The mechanism for varying the extent of oscillation of the cam P and also the mechanism for limiting the longitudinal movement of the cam will now be described in detail.

A roller $20'$, Figs. 11 and 12, is mounted on a shaft $21''$ and is provided with chain wheels $20''$. A chain 20 is trained about and adapted to be rotated by said wheels and is provided with a plurality of adjusting projections $20'''$ preferably arranged in two rows. The projections of each row traveling in the path of and serving to engage separate mechanisms imparting variable oscillatory and reciprocatory movement to the cam P . Next describing the first mentioned mechanism the same comprises a lever 37 mounted on shaft 35 and provided with a finger 36 which as shown is located in the path of the right row of projections $20'''$ with reference to Fig. 11. Said lever 37 is provided with a pin 38 adapted to engage a collar 39 rigidly mounted upon a reciprocating rod 40 . A fork 41 secured on said rod engages the hub 42 of a roller 43 . Said roller 43 is mounted upon a pin 44 secured to the lever v' and is adapted to be reciprocated on said pin in a manner to be brought into register with a plurality of actuating cams 45 , 46 , 47 and 48 mounted on shaft K . A spring 54 normally holds said fork 41 in a retracted position illustrated in Fig. 12. It will be noted by reference to Fig. 12 that the adjusting projections $20'''$ are not only of different lengths but that the same are spaced apart in such a manner that spaces are provided so the lever 37 will not always be actuated and it will be understood that when the spaced portions of said chain register with the finger 36 no movement of the bar or lever 37 will be effected and the roller 43 will be 130

held by spring 54 in engagement with the cam 45. If the shortest of said projections 20''' engage the finger 36 the roller 43 will be shifted to cam 46 and if the next longer 5 projection engages the finger 36 the roller 43 will be shifted to cam 47 and likewise if the longest projection engages the finger 36 the wheel 43 will be shifted to cam 48. It will be obvious from the foregoing that the 10 rocking movement of the lever v' will be varied in accordance with the cam which the roller 43 engages and that the lever u connected with the oscillating pin t will thereby impart an oscillatory movement to the cam P in accordance with the movement of the 15 lever v' .

The mechanism for effecting variable displacement of the cam P longitudinally will now be described in detail.

20 The wedge block l is provided with an arm 33 connected at 29' to arm 29 which is reciprocated by a cam 32. When the lever 29 descends the part s^2 engages the roller s' on the lever s and forces the same outwardly 25 which outward movement is communicated to the cam P by parts q and p . It will be understood that at each revolution of the cam 32 a definite outward movement is imparted to the lever s and cam P and that 30 when lever 29 rises, freeing the lever s the same is retracted by means of a spring hereinbefore described. The means for varying the longitudinal adjustment of said cam consists of the following structure. A lever 35 53 mounted on shaft 35 is provided with a finger 52 located in the path of and adapted to be engaged and actuated by the left hand row of adjusting projections 20''' with reference to Fig. 11. A spring 53^a serves to 40 normally maintain said lever in a position shown in Fig. 12. Said lever 53 is provided on its outer end with an arresting member provided with a stepped engaging surface 55 projecting into the path of and 45 adapted to be engaged by an arresting bolt 56 mounted on lever s . Said lever s is provided with a roller 58 adapted to engage the upper surface of said arresting member. When the wedge block l is reciprocated 50 downwardly and the lever s is thrown outwardly by engagement of the part s^2 with the roller s' one of the projections 20''' will have engaged the finger 52 forcing the lever 53 downwardly and upon return movement 55 of the lever s the bolt 56 will engage one or other steps 55 thereby limiting arresting such return movement of the lever s and thereby fixing the longitudinal position of the cam P . If the finger 52 is not engaged 60 by one of the projections the lever s will be permitted to make a complete return movement.

The chain 20 is given an intermittent movement by means of the following structure. The ratchet 21' is mounted upon the

shaft 21'' and is adapted to be engaged by a pawl 21. Said pawl 21 is carried by an arm 22 loosely mounted on shaft 21''. A link 23 is connected at its upper end with arm 22 and at its lower end with a lever 25 by a 70 pivotal union 24. Said lever 25 is pivoted at 26 and is provided with an extension 26' to which is connected one end of a spring 27 serving to hold said lever 25 in an elevated position. A hook 28 pivotally mounted at 29' on lever 29 is located in the path of the lever 25 and serves to engage and depress the same upon each descent of the lever 29 thereby causing the pawl 21 to rotate the ratchet wheel 21' a distance equal to 80 the length of one tooth thereof. As the lever 29 rises releasing engagement of the hook 28 with the lever 25 the spring 27 restores the lever 25 to a position enabling the pawl 21 to engage the next rearmost tooth of 85 the ratchet wheel.

Now when the plated thread-guides have received their position in front of the respective pattern-point, *i. e.* when the positioning movement has taken place, then the 90 operating movement, to wit the placing of the thread around the frame needle is effected and for this purpose the guide-body receives a short rotation by means of the device t , u . This rotation takes place while the wedge l is at the upper position, that is to say when the pincers i are closed, as shown in Fig. 5. If for instance the guide-body receives a rotation in the direction of the arrow z it will thereby be removed for a 100 small distance in the direction of the arrow y' , because the two centers of the rollers e , f are fixed at this moment. This rotation in the direction of the arrow z may be so large as to cause the rollers e , f to move on for 105 one or two steps of the pattern cam. Now as the difference from step to step is one needle division, simultaneously with the distortion in the direction of the arrow z a placing of the plated thread would be effected in the pattern for one or two needle divisions to the left. If the pattern cam would have received a rotation in the reverse direction of the arrow z the plated thread must have been placed at one or two 110 needle-divisions to the right.

Having now fully described our invention we declare that we claim is:—

1. In combination, a main patterning mechanism, an auxiliary patterning mechanism adapted to shift said main patterning mechanism and comprising a shifting rod, a cam bracket rigidly secured thereto, a cam shaft mounted on said bracket, a cam mounted on said shaft and provided with 120 cam surfaces offset with respect to each other in vertical and horizontal planes, pivotally mounted arms, means for holding said arms in engagement with said off-set surfaces, and means for oscillating said cam 125 130

to bring new surfaces into engagement with said arms and thereby effect longitudinal movement of said shifting rod.

2. In combination, a main patterning mechanism, an auxiliary patterning mechanism adapted to shift said main mechanism comprising a shifting rod operatively connected therewith, a stepped cam for operating said shifting rod, means for engaging said cam, mechanism for oscillating said cam with respect to said engaging means to effect shifting movement of said rod, and mechanism for adjusting said cam longitudinally of its axis.

15 3. In combination, a main patterning mechanism, an auxiliary patterning mechanism adapted to shift said main mechanism and comprising a shift rod, a cam bracket mounted on said rod, a cam movably mounted in said bracket, said cam being provided with horizontally and vertically offset portions, pivotally mounted pincer arms engaging said stepped portions, means for oscillating said cam to bring different off-set surfaces into engagement with said pincer arms to effect the shifting movement, said means comprising a lever secured to said cam and provided with a shiftable cam wheel, a plurality of cams adapted 30 to operate said wheel to vary the extent of oscillation of said cam, and means for shifting said cam wheel.

4. In combination, a main patterning mechanism, an auxiliary patterning mechanism adapted to shift said main mechanism comprising a shifting rod, a cam for shifting said rod provided with horizontally and vertically offset portions, means engaging said off-set portions to normally hold 40 the cam in a given position, and mechanism for oscillating said cam to bring different portions into engagement with said means and effect shifting movement of said main patterning mechanism.

45 5. In combination, a main patterning mechanism, auxiliary mechanism for shifting said main mechanism comprising a shifting rod, a cam associated with said shifting rod and provided with vertically and horizontally offset stepped portions, pincer arms engaging said stepped portions to normally hold the cam in a given position, a wedge plate holding said arms in an engaging position provided with cam surfaces 50 whereby said arms may be released, a lever for shifting said cam longitudinally of its axis provided with a roller engaged by a projection on said wedge plate, an arresting member adapted to engage said lever and 55 arrest movement thereof to fix longitudinal adjustment of said cam and a chain provided with a plurality of adjusting projections adapted to operate said arresting member.

60 6. In combination, a main patterning mech-

anism, auxiliary mechanism for shifting said main mechanism comprising a shifting rod, a cam associated with said shifting rod and provided with vertically and horizontally offset stepped portions, pincer arms engaging said stepped portions to normally hold the cam in a given position, a wedge plate holding said arms in an engaging position provided with cam surfaces whereby said arms may be released, a lever for shifting 70 said cam longitudinally of its axis provided with a roller engaged by projection on said wedge plate, an arresting member adapted to engage said lever and arrest movement thereof to fix longitudinal adjustment of 75 said cam, and means for operating said arresting member.

7. In combination, a main patterning mechanism, auxiliary mechanism for shifting said main mechanism comprising a shifting rod, a cam associated with said shifting rod and provided with vertically and horizontally offset portions, pincer arms engaging said off-set portions to normally hold the cam in 80 a given position, a reciprocating wedge plate holding said arms in an engaging position and provided with cam surfaces whereby said arms may be released, said wedge plate being provided with a cam lug, a spring controlled lever for shifting said stepped 85 cam longitudinally of its axis and provided with a roller engaged by said cam lug, an arresting member adapted to engage said lever to arrest movement thereof and thereby serving to fix longitudinal adjustment 90 of said stepped cam, a chain provided with two rows of adjusting projections, one row engaging and operating said arresting member, a lever for oscillating said cam, a shiftable cam roller carried thereby, a plurality 95 of operating cams adapted to coöperate with said roller to vary oscillating movement of said stepped cam, and mechanism for shifting said roller, said mechanism being operated by the remaining row of adjusting projections.

8. In combination, a main patterning mechanism, auxiliary mechanism for shifting said main mechanism comprising a cam provided with vertically and horizontally offset stepped portions, means engaging said stepped portions to normally hold the cam in a given position, means for oscillating said cam to effect said shifting movement, means for effecting adjustment of said stepped cam 100 longitudinally of its axis, and a chain provided with two rows of adjusting projections, adapted to coöperate with said oscillating and longitudinally adjusting means to control the extent of oscillation and longitudinal adjustment of said cam.

9. In combination, a main patterning mechanism, auxiliary mechanism for shifting said main mechanism comprising a cam provided with vertically and horizontally off- 105

set stepped portions, means engaging said stepped portions to normally hold the cam in a given position, means for oscillating said cam to effect said shifting movement, 5 means for effecting adjustment of said stepped cam longitudinally of its axis, and a device adapted to cooperate with said oscillating and longitudinally adjusting means to control the extent of oscillation 10 and longitudinal adjustment of said cam.

10. In combination, a main patterning mechanism, a cam operatively associated with said mechanism for shifting the same, mechanism for oscillating said cam, mechanism 15 for shifting said cam, means engaging said cam whereby oscillating and shifting movements imparted thereto serve to shift said patterning mechanism, an automatic device for retaining and releasing said 20 means to and from an engaging position with said cam, said device engaging said shifting mechanism to actuate the same when said means is released from engagement with said cam, an arresting device for 25 limiting shifting movement of said cam, a plurality of cams and adjustable mechanism coöperating therewith for operating said oscillating mechanism, and controlling means for adjusting said arresting device 30 and said adjustable mechanism to vary the extent of oscillation and shifting movement imparted to said cam.

11. In combination, a main patterning mechanism, a cam operatively associated 35 with said mechanism for shifting the same, mechanism for oscillating said cam, means engaging said cam whereby oscillating movement imparted thereto serves to shift said patterning mechanism, an automatic device 40 for retaining and releasing said means to and from an engaging position with said cam, a plurality of cams and adjustable mechanism coöperating therewith for operating said oscillating mechanism, and controlling means for adjusting said adjustable 45 mechanism to vary the extent of oscillation imparted to said cam.

12. In combination, a main patterning mechanism, a cam operatively associated 50 with said mechanism for shifting the same, mechanism for oscillating said cam, mechan-

ism for shifting said cam, and means including pincer arms and a wedge block provided with cam surfaces coöperating with said cam whereby movement imparted thereto serves to shift said patterning mechanism, said wedge block engaging said shifting mechanism to operate the same. 55

13. In combination, a main patterning mechanism, a cam operatively associated 60 with said mechanism for shifting the same, an oscillating bar connected with said cam, adjustable means carried by said bar, a plurality of cams associated with said means to actuate said bar, a controlling device for 65 adjusting said means to vary the extent of oscillation of said cam, and means engaging said cam whereby movement imparted thereto serves to shift said main patterning mechanism. 70

14. In combination, a main patterning mechanism, a cam operatively associated 75 with said mechanism for shifting the same, an oscillating bar connected with said cam, adjustable means carried by said bar, a plurality of cams coöperating through said means to oscillate said first mentioned cam, a shifting lever connected with said cam, means engaging said cam whereby movement imparted thereto serves to shift said 80 main patterning mechanism, said means engaging said shifting lever to operate the same in one direction, an arresting member limiting movement of said shifting lever, and a controlling device for moving said adjustable means to effect variable oscillation 85 of said cam, said controlling device also serving to control said arresting member. 90

15. In combination, a main patterning mechanism, a shifting rod operatively connected therewith, a cam mounted on said rod, means engaging said cam, and means for operating said cam to effect movement of said shifting rod. 95

In testimony whereof we affix our signatures in presence of two witnesses.
